DOOR OPERATOR

Earl B. Spencer, La Canada, Calif., assignor to
Whiting Corporation, Harvey, Ill., a corpora-
tion of Illinois

Application November 1, 1948, Serial No. 57,699

3 Claims. (Cl. 20—24)

1

This invention relates to doors, and more particularly relates to doors intended and adapted to be tightly sealed, though not necessarily locked, to prevent the passage of air or sound from one side of a wall to the other, such as the doors of sound stages and other chambers where the exclusion of sound, drafts, and temperature changes is important.

It is to be understood that modern sound stages, as used in the motor picture and radio broadcasting industries, require doors of massive proportions providing passage space for vehicles and for stage sets. Space requirements frequently do not permit such doors to be swung on hinges in the ordinary manner, and indeed the weight and leverage of such doors would require door frames of extraordinarily heavy and expensive construction, were the doors to be hinged thereon. Sliding doors are the most practical form, from considerations of space and wall construction, but they in turn raise problems in connection with sealing them tightly and moving them. It is desirable to equip doors for a sound stage with tight-sealing resilient marginal strips which leave no cracks for the passage of sound. However, lateral sliding movement of a door affords opportunity to seal such a strip only on the edge of the door leading the closing movement, except by compressing strips on the other edges of the door by prolonged wedging movement engendering a large amount of friction and making it difficult to move the door in either direction.

To overcome the above stated difficulties and to obtain a tight seal with a sliding door, door mountings have been devised in which the door is hung on a hinge member pivotally mounted on an overhead trolley or carrier rolling on an overhead rail, with the hinge member arranged to swing about its pivot on the carrier so as to move its point of support of the door arcuately, the door remaining in a substantially vertical plane as dictated by gravity. With such an overhead suspension, and with the door arranged to swing downwardly and toward the door jamb, and upwardly away from the jamb while all the time hanging vertically, clamping mechanism has also been devised, actuatable by the free swinging weight of the door, to move the door positively towards the jamb through a series of planes parallel to the plane of the doorway and so to compress sealing means arranged around the margins of the door and of the doorway.

It is further desirable, in doors for sound stages, to provide two doors forming an air lock, so that

2

a person passing through the doorway may open one door, enter the lock, and close the first door before opening the second, so as to maintain a barrier against the passage of sound. Obviously the controls for such an air lock should be operable from either side of the lock and from within the lock, although to permit the doors to slide along the wall the bulk of the actuating mechanism is preferably on the outer side of each door. Furthermore, such controls should be as soundless as possible, eliminating the rattling of chains and bolts, and should require no openings or passages through either the doors or the wall to accommodate such linkage mechanisms as chains, cables, or connecting rods. It is also desirable that each door of a lock be operable entirely independently of each other.

It is therefore an object of this invention to provide a door for the purposes stated herein which may be moved between sliding and sealing positions by mechanism disposed on one side of the door and operable from either side thereof.

Another object of the invention is to provide substantially silent mechanism for moving a sliding door into and out of sealing engagement with a door jamb.

A further object of the invention is to provide sealable sliding doors and operating mechanism therefor, suitable for forming closures to an air lock passage through a wall.

Still another object of the invention is to provide operating mechanism for doors forming an air lock which may be controlled independently for each door and from positions on both sides of each door by dual systems of control, so as to minimize the chance of a person being imprisoned within the air lock.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred forms within the scope of my invention as set forth in the claims.

In the accompanying drawings, the door embodying this invention is shown in duplication on opposite sides of an air lock, such a construction having the advantages above set forth with respect to excluding sound from a sound stage or studio while a person is entering or leaving. The dual construction is also useful for illustrative

purposes, one door being shown open and the other door closed, to afford ready comparison of the positions of the operating mechanism in the two positions of a door. It will be understood, however, that the door herein illustrated and described may be used singly in conditions not requiring an air lock, and while the features of the invention render the door particularly adapted for air lock use, the invention may be embodied in either a single or duplicated arrangement of a door.

Figure 1 is an elevational view of a sound stage wall provided with two doors embodying this invention, showing one door in open position in full line, and the other door in closed position in broken line as it would appear on the opposite side of the wall.

Figure 2 is a vertical sectional view on an enlarged scale, the plane of section being indicated by the line 2—2 of Figure 1, and illustrates the mechanism by which the doors are moved slidably parallel to the wall, and the mechanism for lifting and lowering the doors through parallel vertical planes.

Figure 3 is a horizontal sectional view showing the air lock formed by the two doors, one of which is shown closed and sealed, and the other is shown swung outwardly from the door jamb as if to be opened.

Figure 4 is a vertical sectional view taken on the plane of section 4—4 of Figure 3, with the direction of view as indicated, and shows the clamping mechanism for clamping the doors to the door jambs, the mechanism applicable to the leading edges of the doors in the closing direction of movement being illustrated.

Figure 5 is a fragmentary elevational view of the lower portion of a door jamb, showing the stop for checking the descent and thereby actuating the clamping mechanism.

Figure 6 is a fragmentary vertical sectional view taken through one of the doors to illustrate the mounting of the control handles on the outer and inner sides of the door, the plane of section being indicated by the line 6—6 of Figure 1, with the direction of view as indicated.

Having reference to the details of the drawings, a wall 10 is shown provided with a doorway 11, for which a door 13 serves as a closure. The wall 10 may be of sufficient thickness to provide space between its surface for an air lock, closable on the side opposite the door 13 by another door 14. Overhead rails 15, preferably of the mono-rail type, are secured to the wall 10 above the doorway 11 and extend beyond the doorway on both sides of the wall 10 to support the doors 13 and 14. Carriers or trolleys 16, preferably two for each door, are mounted to roll on the rails 15, each comprising wheels 17 mounted on V-frames 18 which depend below the rails. The V-frames 18 of each carrier 16 are connected by connecting links 19 which have lugs 20 spaced apart to receive the ends of pins 21. The pins 21 serve as fulcrum points for the hereinafter described lever mechanism.

The doors 13 and 14 being alike, only one will be described. Each door comprises a door panel 24, to the upper margin of which are secured bearing brackets 25 holding rotatably a shaft 26. The shaft 26 has laterally extending arms 27 pivotally engaging the pins 21 of the carriers 16 respective to the particular door so that the shaft 26 may be swung about the pins 21 as axes. The shaft 26 also has an arm 28, extend-

ing oppositely from the arms 27 and pivotally secured at its distal end to a piston 29 extruding from a cylinder 30. The cylinder 30 is pivotally mounted in brackets 31 secured to the panel 24. It will be seen that the shaft 26 with its arms 27 and 28 forms a lever fulcrumed at the distal ends of the arms 27 and with power applicable at the distal ends of the arms 28 by the piston 29 to swing the shaft 26 and the door suspended therefrom about the fulcrum pins 21, and that the door is freely hung upon the shaft 26 by the bearing brackets 25 and will tend to maintain a vertical plane, as dictated by gravity.

The cylinder 30 and piston 29 are hydraulically operated by fluid from a reservoir 34 carried on the upper margin of the door. Preferably two pumping systems are provided for pumping fluid from the reservoir 34 to the cylinder 30. A conduit 35 leading from the reservoir 34 is divided to lead through a conduit 36 to an electrically operated pump 37 driven by a motor 38 and through a conduit 39 to a manually operated pump 40. The pump 37 and the motor 38 therefor may be secured to the upper margin of the door, adjacent to the reservoir 34 and the pump 40 is preferably disposed on the outer side of door at a height convenient for manual operation. Conduits 41 and 42, leading respectively from the electric pump 37 and the manual pump 40, join in a cross-fitting 43 from which a conduit 44 extends to the cylinder 30, terminating in a flexible connection 45 to permit oscillation of the cylinder in its brackets 31. The conduit 41 is provided with a check valve 46 to prevent return flow to the pump 37, and the conduit 42 is similarly provided with a check valve 47 to prevent return flow to the pump 40. The conduits 39 and 42 are connected by a conduit 48 entering the conduit 42 between the check valve 47 and the cross-fitting 43 and provided with a hand valve 49 disposed conveniently to the manually operated pump 40. A conduit 50 leads from the cross-fitting 43 to the reservoir 34 and is provided with a solenoid operated valve 51 which is normally closed.

It will be understood that electric power for the motor 38 and for the solenoid operated valve 51 may be conducted from terminals on the wall 10 to the doors 13 and 14 by flexible cables of conventional type, the arrangement of which it is not deemed necessary to show. Similarly, the arrangement of the control wiring to the motor 38 and to the solenoid operated valve 51 is optional and is not shown in detail.

Push button panels 54 and 55 are shown in Figure 1 disposed on the outer side of the door 13 and the inner side of the door 14, and it will be understood that both doors have such panels disposed at both of their sides, either on the doors themselves or conveniently situated on the wall 10, so that the motor 38 and valve 51 respective to each door may be controlled by suitable switches from both sides of the particular door. Likewise omitted from the drawings as optional and as confusing to more essential points of illustration, are underdrive mechanisms connecting the doors to the rails 15, as fully described and illustrated in my United States Patent No. 2,317,689, issued April 27, 1943, such mechanism being desirable when heavy doors are to be rolled aside and being controllable by switch mechanism at the panels 54 and 55.

The manually operated pump 40 and the fluid control system above described is preferably dis-

posed on the outer side of its respective door to permit the door to be rolled aside past the wall 10. The pump 40 is operated by means of a handle 57 secured to a shaft 58 extending rotatably through the wall to the inner side thereof. A handle 59 on the inner end of the shaft 58 permits operation of the pump 40 from the inner side of the door. The shaft 58 may be packed tightly to prevent passage of sound, in a manner not possible with a longitudinally moving cable or chain.

The doorway 11 has marginal pads 62 secured to jamb strips 63 around its lateral and overhead margins. The pads 62 may be of rubber or like material, adapted to form a resilient seal when under compression. To guide the doors 13 and 14 in their lateral rolling movement, rollers 64 may be secured to the jamb strips 63 close to the floor and rollers 65 may be secured to the floor outside of the doors and laterally beyond the margins of the doorway 11. Floor stops 66 may be provided to limit the opening movement of the doors, and wall stops 67 are desirable to arrest the closing movement of the doors just prior to contact of the hereinafter described clamping irons to avoid strain upon the latter. Wear strips, such as shown at 68 in Figure 3, may be provided for the various rollers to roll against.

As best shown in Figures 3 and 4, the lateral jamb strips 63 adjacent the margin of the doorway 11 toward which the doors open support clamping irons 71. The clamping irons 71 are angle irons having one flange secured to the jamb strips 63 and the other flange 72 spaced from the wall 10 and directed in the direction of opening movement of the door. Clamping irons 73 are secured to the wall 10 adjacent the margin of the doorway 11 toward which the doors close, and may be angle irons bolted together to form a channel opening toward the doorway 11, so that the flanges 74 spaced from the wall are pointed in the same direction as the flanges 72 of the irons 71.

Clamping irons 76 and 77, of angle iron form, are secured movably to the end margins of the door panel 24 with free flanges 78 and 79 directed in the direction of closing movement of the door so as to be able to interlock with the flanges 71 and 74. To support the clamping irons 76 and 77, angle irons 80 and 81 are secured to the panel 24, the angle 81 being turned outwardly to retract the clamping iron 77 to a position in which it will clear the pads 62 while still being engageable with the extended clamping iron 73. Linkage bars 82, pivoted at both their ends, connect the clamping irons 76 and 77 to the angle irons 80 and 81 so that the clamping irons and the door are relatively movable but are always parallel, and with the linkage bars form sides of parallelograms of varying obliquity. Angle irons 83 are secured at intervals to the angle irons 80 and 81 and extend across the parallelograms to the clamping irons 76 and 77, but do not connect thereto. Bolts 84, threaded in brackets 85 on the clamping irons 76 and 77, are disposed to make contact with the angle iron 83 and to confine downward movement of the clamping irons relative to the door 24, and upward movement of the door relative to the clamping irons, to limits adjustable by adjusting the bolts. Downward movement of the clamping irons 76 and 77 relative to the doorway 11 is limited by stops 86 adjustably secured to each of the clamping irons 71 and 73. A bolt 87 extends through the clamping iron and through a slot 88 in the stop 86, to clamp the stop in an

adjusted position. A set screw 89, threaded in a lug 90 bears against the stop 86 to adjust the height of the stop as may be desired.

In descending movement of a door when it is opposite the doorway 11, the clamping irons 76 and 77 will be resting by gravity upon the angle irons 83, until the feet of the clamping irons make contact with the stops 86. Continued descending movement of the door causes the door to swing inwardly and downwardly towards the doorway 11, but always parallel to the plane of the wall 10 as compelled by the arcuate movement of the linkage bars 82, and by immobilization of the clamping irons 76 and 77 by the stops 86 and the interlocking clamping irons 71 and 73. The inner faces of the doors 13 and 14 are provided with sealing pads 92 on their lateral and upper margins which register with and compress against the sealing pads 62, and the lower margin of each door has a sealing pad 93 which seals the door against the floor as the door descends.

A person desiring to pass through a door embodying this invention will normally utilize the electric controls, the manual controls comprising the manually operated pump 40 and the handles 57 and 59 being available if the electric power is cut off, or in other emergencies. Assuming the person to desire to pass through the closed door 14, from the rear of that door as shown in Figure 1 or from the left as shown in Figure 3, the electrically operated pump 37 may be started by controls acting in conjunction with the controls of the panel 55 and situated on the outside of the door 14, corresponding to the panel 54 on the door 13. Fluid from the reservoir 34 is then pumped through the conduits 35, 36, 44, and 45 to the cylinder 30 to extrude the piston 29 and to cause the lever mechanism formed by the shaft 26 and its arms 27 and 28 to raise the door as shown at the right in Figure 2. As the door is lifted, the clamping irons 76 and 77 do not lift at once, but remain upheld by the clamp stops 86, while the door panel 24 and the attached angle irons 80 and 81 swing outwardly and upwardly. At an adjustable point in this swinging movement, the stop bars 83 come into contact with the bolts 84, and continued movement will raise the clamping irons 76 and 77 from the clamp stops 86. The swinging movement of the door panel 24 releases the bottom pad 93 from the floor and the marginal pad 92 from the pads 62 with practically no sliding movement of one pad upon another.

It will be noted that the clamping irons 76 and 77 still overlap the jamb clamping irons 71 and 73 as shown in the lower half of Figure 3. However, the door may now be rolled along the track 15, either manually or by means of the above-mentioned underdrive mechanism. When the person has passed to the other side of the door, the door is returned by the same means to its closed but raised position in which the clamping irons 76 and 77 again interlock with the clamping irons 71 and 73. A control on the panel 55 in circuit with the solenoid operated valve 51 is then operated to open the valve and to release the fluid in the cylinder 30 to the reservoir 34, permitting the door to swing downwardly and inwardly against the door jamb.

At the start of this downward movement, the clamping irons 76 and 77 move with the door until they reach the clamp stops 86. Their movement is then arrested and further downward movement of the door causes the door to be pulled inwardly toward the door jamb by the linkage

bars 82. The movement of the door is necessarily towards the door jamb because the clamping irons 76 and 77 are interlocked with the clamping irons 71 and 73 and cannot move outwardly. The door, swinging by its own weight and held by the linkage bars 32 in a vertical plane, thus comes to rest upon the pad 93 upon the floor with the pads 92 compressed against the pads 62 and the door thus sealed around its whole perimeter.

When the door is sealed against the door jamb, the control for the solenoid operated valve 51 is released, to permit the valve to close.

If electric power is not available, the manually operated pump may be used to raise and to lower the door. The hand valve 49, like the solenoid valve 51, is normally closed. Operation of the pump 40 by the handles 57 or 59 draws fluid through the conduits 35 and 39 to the pump and thence through the conduits 42, 44, and 45 to the cylinder 30 to raise the door. When the door is to be lowered again, the hand valve 49 is opened and the fluid returns to the reservoir 34 through the conduits 45, 44, 42, 48, 39, and 35, bypassing the pump 40 and the check valve 47.

Operation of two doors successively as an air lock is performed as above described, first on one door and then on the other. The second door remains sealed while a person unseals the first door, opens and closes it to enter the lock, and then reseals it. Consequently, external sounds may be excluded from the sound stage provided with such a lock while a person enters or departs through the lock. The manually operated controls on the inside of the lock are safeguards against imprisonment of a person within the lock in the event of sudden power failure.

I claim:

1. A closure device for a building doorway comprising a door, overhead support means for the door including a carrier movable laterally above the doorway, an arm pivotally connecting the carrier and the door, means for moving the arm and door upwardly and outwardly away from the doorway, a first door clamp fixed to the building, a second door clamp pivoted at one end to the door for lateral movement therewith and having a member on its free end for engagement with the first door clamp as the door is moved laterally across the doorway into closed position, first stop means carried by the door for limiting downward movement of the second door clamp to a horizontal position, and second stop means on the first door clamp for limiting downward movement of the free end of the second door clamp after said clamps engage, whereby downward movement of the door, after engagement of the clamps swings the door inwardly against the doorway.

2. A closure device for a building doorway comprising a door, overhead support means for

the door including a laterally sliding carrier, lever means pivotally connecting the door and carrier, means for actuating the lever in a direction lifting the door arcuately upwardly and away from said doorway, a fixed clamping member marginal to the doorway including an upright, laterally extending flange spaced outwardly from the doorway, a second upright clamping member carried by the door including a laterally extending flange disposed for interlocking engagement with the flange of the first clamping member as the door is moved laterally into closed position, parallel arms each pivoted at one end to the second clamping member and pivotally fixed at the opposite end with respect to the door for lateral movement therewith, means for holding the second clamping member in extended position away from the door when the door is open, and means for limiting downward movement of said second member when engaged by the first member.

3. A door clamping device for building doors of the type suspended from a laterally movable overhead carrier for upward and outward movement away from the building upon opening and downward and inward movement towards the building upon closing comprising a movable rigid clamping member having one portion pivotally secured to the door for movement about a generally horizontal axis and a second portion arcuately movable with the first portion in a generally vertical plane transverse to the door, the second clamping member fixed with respect to the building and disposed in the path of said second portion of the movable clamping member for interlocking engagement therewith as the door is moved laterally into closed position, and stop means fixed with respect to the second clamping member for limiting downward movement of the second portion of the rigid clamping member after engagement of said members, whereby as the door is lowered the stop means is engaged by said second portion and the movable clamp member pivots to force the door inwardly against the building.

EARL BURTON SPENCER.
